UNITED STATES PATENT OFFICE.

JACUB SCHWARTZMAN, OF BROOKLYN, NEW YORK.

WIRE FABRIC.

1,192,943.

Specification of Letters Patent.

Patented Aug. 1, 1916.

Original application filed July 18, 1913, Serial No. 779,677. Divided and this application filed September 25, 1914. Serial No. 863,479.

To all whom it may concern:

Be it known that I, JACUB SCHWARTZMAN, a citizen of the United States, residing at Brooklyn, in the county of Kings and State 5 of New York, have invented certain new and useful Improvements in Wire Fabrics, of which the following is a specification.

This invention relates to wire metallic fabrics, the object of the invention being 10 to provide an improved fabric of this character particularly adapted for use in connection with spring mattresses, which will be simple in construction, durable in use, and comparatively inexpensive to manufacture, especially in view of the fact that it 15 requires a minimum amount of wire in its construction, made up of an improved form of links, quickly and inexpensively assembled, and in which the pull on the several 20 links of the fabric will be in a straight direction lengthwise of the fabric, and which links are so constructed and assembled that they will not draw the edges of the fabric toward the middle by reason of the length- 25 wise pull on the links, while at the same time the fabric will be unusually resilient and may be readily folded along longitudinal lines, which is desirable when the fabric is to be applied for use in folding cots, divans 30 and other folding structures.

The present improvement is a division of my Patent No. 1,116,500, dated November 10, 1914.

In the drawings accompanying and forming part of this specification, Figure 1 is a 35 plan view of a plurality of links of the exact size as usually used, assembled; Fig. 2 is a plan view showing the improved fabric made up of a number of units or links; Fig. 3 is a detail view, full size, of one of the 40 improved links for the body of the fabric; Fig. 4 is an edge view of the link shown in Fig. 3; and Fig. 5 is a detail view illustrating another way of assembling the same form 45 of links, the links being shown full size.

Similar characters of reference indicate corresponding parts throughout the several figures of the drawings.

In the form shown, the fabric is made up 50 of a series of interconnected or interwoven units or links 2, each comprising a pair of relatively straight portions 3 and 4 running in substantial parallelism with each other and connected at their ends by a cross-form-

ing portion 5, thus forming a link somewhat 55 resembling a capital letter U. The straight portions 3 and 4 of the link terminate in hooks or loops 3' and 4' respectively at one end of the link, these hooks being in alignment with the straight portions and are 60 closed when the link is made; in other words, before the links are assembled and not subsequent to the assembling of the links. At the opposite end, or what may be considered 65 the head portion, of the link, each of these lengthwise extending portions 3 and 4 merges into an angular-formed portion 6 made up of a pair of inclined portions 7 and 8, each of which may be slightly curved, which inclined portions 7 and 8 at their 70 juncture points are offset one from the other as at 9, that is, it is given a half twist whereby the several links may be readily interwoven with each other, the inclined portion 7 in turn being bent inwardly as at 10 to 75 form an eye or loop 11 of somewhat triangular form and therefore resembling somewhat the shape of an inverted V, such loop or eye terminating in the cross member 5. Each angular formed portion extends outwardly so that the link at this point is of 80 greater width than at any other point thereof, while the cross member 5 is located inwardly of the extreme end of the link and is comparatively short, and the straight portions 3 and 4, if continued, would merge into the inclined portions 10 relatively close to the outer ends of the cross portion 5. 85 In short, the head of each link is considerably wider than the space between the straight portions 3 and 4 thereof for the purpose hereinafter stated. The angular portions of the link hereinbefore described are for the purpose of permitting an efficient and effective interlocking or interweaving 90 of one link with a companion link in the manner shown in Figs. 1 and 2, in which it will be observed that the companion links or units are, as it were, twisted together, this being permitted by reason of the offset 95 portions 9 of each link which constitute the connecting part between the inclined portions forming the triangular portion of the link at this point.

When the several units or links have been 100 assembled in the manner shown in Figs. 1 and 2, they are connected to a supporting or cross-angle bar by helical springs 13, for

which purpose intermediate end links 14 are provided with hooked ends 15 for connection with the eyes 11 of the several links.

In the form shown in Fig. 5 the units or links instead of being connected or interwoven directly, are connected by means of a ring 16 which is interwoven with the triangular portions of the link. It will be observed that by means of the present improvement, the pull on the links is in a straight direction lengthwise thereof and that the straight portions 3 and 4 are not only spaced from each other in each link, but the adjoining straight portions of the several links are likewise spaced from each other a considerable distance, as at 17, and that although the space between the straight portions of a pair of adjoining links is not as great as the space between the straight portions of each link, yet it is sufficiently great to give increased support to the stuffed mattress placed upon the fabric. In other words, by reason of the fact that the straight portions of adjoining links are spaced apart a considerable distance, increased support is given to the mattress, as will be obvious as thereto should such straight portions be brought close together, for in such latter case a pair of links, for instance, would support the mattress practically only at three points, whereas in the present instance the mattress is supported at four points. Moreover, by reason of the fact that the hooks of each link are in alinement with the straight portions, there is no appreciable tendency of the links to draw the edges of the fabric toward the middle and present an uneven edge, which is always a serious disadvantage in any fabric. Moreover, by reason of the fact that the hooks of each link are practically completely closed when formed, and before the fabric is assembled, the links can be quickly interwoven, and furthermore when the links are tinned, the tinning material connects the hooked end with the adjacent portion of the link, thus forming practically an integral loop.

By reason of the present improvement considerable resiliency is obtained both lengthwise and sidewise of the fabric.

One of the advantages, as hereinbefore stated, for the present improvement, is that the links may be quickly and readily formed by machinery just as shown in the drawings, that is with closed hooks or loops, and readily and quickly assembled by inexpensive labor, thus avoiding the necessity of bending the ends to form the hooks subsequent to the assembling of the links.

I claim as my invention:—

1. A wire fabric for bed springs comprising a multiplicity of wire units arranged in rows, each unit consisting of a link having two side members and a connecting end

member having a loop or eye portion at the juncture of each such side and end member, each eye portion terminating in a triangular formed portion having an offset adjacent to the apex thereof thereby to permit one link to be interwoven with a companion link, said links, when interwoven, having the straight portions thereof spaced materially apart to give increased bearing surface to the mattress. 70 75

2. A wire fabric for bed springs comprising a multiplicity of wire units arranged in rows, each unit consisting of a link having two side members and a connecting end member having a loop or eye portion at the juncture of each such side and end member, each eye portion terminating in a triangular formed portion having an offset adjacent to the apex thereof thereby to permit one link to be interwoven with a companion link, said links, when interwoven, having the straight portions thereof spaced materially apart to give increased bearing surface to the mattress, and each of said links having a hook at the end of its straight portion in alinement with such straight portion. 80 85

3. A wire fabric for bed springs comprising a multiplicity of wire units arranged in rows, each unit consisting of a link having two side members and a connecting end member having a loop or eye portion at the juncture of each such side and end member, each eye portion terminating in a triangular formed portion having an offset adjacent to the apex thereof thereby to permit one link to be interwoven with a companion link, said links, when interwoven, having the straight portions thereof spaced materially apart to give increased bearing surface to the mattress, and each of said links having a hook at the end of its straight portion in alinement with such straight portion, said hook being formed prior to the assembling of the links. 95 100 105

4. A wire fabric for bed springs comprising a multiplicity of wire units arranged in rows, each unit consisting of a link having two side members and an end member, the side members terminating adjacent to the end member in a triangular portion having an offset, and the side members of adjacent links being spaced materially apart to give an increased bearing surface. 110 115

5. A wire fabric for bed springs comprising a multiplicity of wire units arranged in rows, each unit consisting of a link having two side members and an end member, the side members terminating adjacent to the end member in a triangular portion having an offset, and the side members of adjacent links being spaced materially apart to give an increased bearing surface and extending in parallelism with one another. 120 125

6. A wire fabric for bed springs compris- 130

- ing a multiplicity of wire units arranged in rows, each unit consisting of a link having two side members and an end member, the end member being located within the ends 5 of the link, and the side members connected with said end member by a pair of bulging triangular formed portions and the side members terminating in hooks in alinement with such side members.
- 10 7. A wire fabric for bed springs comprising a multiplicity of wire units arranged in rows, each unit consisting of a link having two side members and an end member, the end member being located within the ends 15 of the link, and the side members connected with said end member by a pair of bulging triangular formed portions, each having an offset portion therein, and such side members being located within such triangular 20 formed portions and parallel from end to end so that when assembled the side members of adjacent links will be materially spaced apart.
8. A wire fabric for bed springs comprising substantially U-shaped links arranged in longitudinal and transverse rows, each link consisting of a pair of straight portions and a connecting cross portion connected with each straight portion by a pair 25 of triangular formed portions extending in different directions, such straight portions having hooks at their ends in alinement with such straight portions, and said links being joined in transverse rows by the interlocking of certain of such triangular portions, and the hooks of the links of one transverse 30 row engaging certain of the triangular portions of the links of the next transverse row.
- 35 9. A wire fabric for bed springs comprising substantially U-shaped links arranged in longitudinal and transverse rows, each link consisting of a pair of straight portions and a connecting cross portion connected 40 with each straight portion by a pair of triangular formed portions extending in different directions, such straight portions having hooks at their ends in alinement with such straight portions, and said links being joined in transverse rows by the interlocking 45 of certain of such triangular portions, and the hooks of the links of one transverse row engaging certain of the triangular portions of the links of the next transverse row, such triangular and straight portions being 50 so formed that the straight portions of adjacent links are parallel and spaced materially apart to give increased bearing surface.
- 55 10. A link for a wire fabric comprising a pair of parallel straight portions and a connecting end portion and having therebetween an outwardly bulged portion of triangular form having an offset therein, each 60 of such straight portions terminating in a hook in alinement with such straight portion.
11. A link for a wire fabric comprising a pair of parallel straight portions and a connecting end portion and having therebetween an outwardly bulged portion of triangular form having an offset therein, the straight portions of said link being well within the triangular portions so that when the links are assembled the straight portions 70 of adjacent links will be spaced relatively far apart.
12. A link for a wire fabric comprising a pair of parallel straight portions and a connecting end portion and having therebetween an outwardly bulged portion of triangular form having an offset therein, the straight portions of said link being well within the triangular portions so that when the links are assembled the straight portions of adjacent links will be spaced relatively far apart, the straight portions of the link terminating in hooks in alinement with such straight portions.
13. A metal fabric for bed springs comprising a multiplicity of wire units arranged in rows, each unit consisting of a substantially U-shaped link having a pair of triangular portions adjacent to one end, each triangular portion carrying means connecting it with an adjacent link, the several links being so connected that the straight portions of adjacent links are spaced a material distance apart thereby to provide increased bearing surface.
14. A wire fabric comprising substantially U-shaped links arranged in longitudinal rows and transverse rows, each link having the base portions of its arms provided with compound curves and having its web provided near the extremities thereof with offsets and each link having its arms provided with hooked extremities, said links being joined in transverse rows by the interlocking of said arms at said compound curves, and the hooks of the links of one transverse row engaging the offsets of the webs of the links of the next transverse row, said links when interlocked having the straight portions of its arms spaced materially apart 100 throughout the length thereof to give increased bearing surface to the mattress.
15. A wire fabric comprising links arranged in longitudinal rows and in transverse rows, each link comprising a U-shaped member having lateral offsets at the junction of the web and arms and having end offsets at the web, said arms having hooked extremities, and said links being joined in transverse rows by the interlocking of said lateral off-sets and joined in longitudinal rows by the engagement of said hooks with the end offsets of said webs.
16. A wire fabric comprising a plurality of transverse rows of similar U-shaped links 125

with the arms of said links pivotally interlocked at their base portions, said links having hook-engaging eyes at their webs and having their arms provided with hooked extremities, the hooked extremities of the arms of one transverse row of links engaging eyes at the webs of the links of the next transverse row, said links when interlocked having the straight portions of its arms spaced materially apart throughout the length thereof to give increased bearing surface to the mattress.

17. A wire fabric comprising substantially U-shaped links arranged in longitudinal and transverse rows, the arms of the links of each longitudinal row being intertwined with the arms of the links of adjacent longitudinal rows, the arms of the links of a given transverse row being in pivotal engagement with the base-portions of the links of the next transverse row, said links when interlocked having the straight portions of its arms spaced materially apart throughout the length thereof to give increased bearing surface to the mattress.

18. A wire fabric comprising substantially

U-shaped links arranged in longitudinal and transverse rows, the arms of adjacent links being of such form and disposition as to pivotally interlock and be substantially parallel with, and relatively far apart from each other, the arms of the links of one transverse row being in hooked engagement with the links of the next transverse row.

19. A wire fabric comprising substantially U-shaped links arranged in longitudinal and transverse rows, the arms of adjacent links being of such form and disposition as to pivotally interlock and be substantially parallel with each other, the arms of the links of one transverse row being in hooked engagement with the links of the next transverse row, and the arms and the hooks thereof of one transverse row being in substantial alignment with the arms and the hooks of the next transverse row whereby a straight pull from end to end of the fabric is obtained.

JACUB SCHWARTZMAN.
